Primary Examiner — Ian Simmons*Assistant Examiner* — Charles Hanson(74) *Attorney, Agent, or Firm* — Pedersen and Company, PLLC; Ken J. Pedersen; Barbara S. Pedersen(57) **CLAIM**

The ornamental design for an air valve, as shown and described.

DESCRIPTION

FIG. 1 is a side perspective view of the invented design for an air valve.

FIG. 2 is a front view of the air valve of FIG. 1.

FIG. 3 is a rear view of the air valve of FIG. 1.

FIG. 4 is a right side view of the air valve of FIG. 1.

FIG. 5 is a left side view of the air valve of FIG. 1.

FIG. 6 is a top view of the air valve of FIG. 1; and,

FIG. 7 is a bottom view of the air valve of FIG. 1.

The broken line showing is included for the purpose of illustrating environment and forms no part of the claimed design.
